EMBALMING COMPOSITION

Hilton Ira Jones, Wilmette, Ill., assignor to The Naselmo Corporation, Chicago, Ill., a corporation of Illinois

No Drawing. Application February 4, 1935,
Serial No. 4,882

5 Claims. (Cl. 27—22)

My invention relates to the art of embalming and has to do more particularly with an improved composition of matter which is especially adapted for application to the outside of a body, more especially the human body, for the hardening of outer tissues which are not readily affected by the usual hardening solutions introduced into the arterial system of the body.

It has previously been suggested that such outer tissues be hardened by applying to the surface thereof the usual tanning solution, such as formaldehyde or the like, absorbed in a cotton sponge, although this method has never been satisfactory, due to the fact that the solution tends to run off. In order to avoid the difficulties attendant on this procedure attempts have also been made to provide emulsions of tanning agents, as, for example, formalin in oxycholesterin. Such emulsions have been far from satisfactory because of the tendency of formaldehyde to oxidize in the presence of air, resulting in an increase in acidity, whereby the emulsion apparently changes phase from formalin in oxycholesterin to oxycholesterin in formalin. At any rate, the material in which the formalin has substantially changed to formic acid, resulting in a dropping in pH value, has become modified from a viscous and adhesive material to a slimy one which will not adhere to the skin of the body.

An object of my invention is to provide a substantially permanent stable emulsion of a tanning agent which is normally oxidized to form an acid, such as formaldehyde, an emulsion of which, after such oxidation, will normally tend to break or reverse phase, as described above. I have found that I can stabilize such an emulsion through the use of a buffer salt which will tend to prevent any substantial drop in pH as a result of the oxidation of the tanning agent.

My preferred buffer is sodium racemic lactate. However, various alternative buffers may be used with satisfactory results, such as sodium tartate, sodium citrate, and the like.

In accordance with a preferred method of practicing my invention, a fatty substance, together with the buffer material, is emulsified with the tanning agent in aqueous solution, said emulsion being stabilized by means of a suitable emulsifying agent, such as a soap, and the material is preferably thinned to the desired consistency by beating mineral oil into it.

Example

The following formula is given as an example of one manner of practicing my invention, al-

though it should be understood that said formula is not to be considered as limiting with regard to the ingredients or proportions thereof:

	Parts by weight	5
Oxycholesterin	20	
Formalin	80	
Mineral oil	10 to 20	
Sodium racemic lactate	3	
Liquid soap 15%	5	10

In lieu of oxycholesterin I may use metacholesterin or iso-cholesterin, or mixtures of these materials in any desired proportion. Various other fatty substances may also be used, for example, lanolin.

The fatty material and formalin are usually whipped together, the formalin being added gradually as the emulsification progresses. For this purpose I may use a Hobart mixer or any other suitable device. The emulsifying agent is preferably added after about three-fourths of the formalin has been added. The result should be a composition of buttery or harder consistency. The liquid soap is then added and the material is whipped again. While I have specified mineral oil above, substantially any neutral oil of the required viscosity will be satisfactory. Oil may be beaten into the material in any quantity to give the desired consistency which will permit the material to adhere to the skin of the body.

If desired, a perfume may be used, which may be incorporated in the oil.

It will be understood that other tanning agents may be used in lieu of formalin. For example, para-formaldehyde or a formaldehyde paste, such as is readily obtainable on the market, one such paste consisting of about 90 parts of formalin incorporated with 10 parts of glycol-stearate. In the claims, where the word "formaldehyde" is used, this will be understood to include the various modifications of formaldehyde herein discussed which would be obviously equivalent for my purposes.

In another mode of practicing my invention, glycol stearate (di-glycol stearate) may be emulsified with 40% formalin, at an elevated temperature, in the ratio of about 1 to 4 parts by weight (1 stearate to 4 formalin). The emulsion thus formed jells on cooling to form a paste, which is beaten into oxycholesterin, and the other ingredients, such as emulsifier, soap, and oil are introduced as described above. This method is found especially convenient.

Various other modifications coming within the spirit of my invention will doubtless suggest them-

selves to those skilled in the art. Hence I do not wish to be limited to the details given above except to the extent indicated by the appended claims, which are to be interpreted as broadly as 5 the state of the art will permit.

The word "tanning" is used herein in the sense of hardening.

I claim:

1. A plastic embalming composition especially 10 adapted for hardening tissues from the outside of the body and of sufficiently solid consistency to adhere to the surface thereof, comprising an emulsion of formaldehyde in a fatty substance and including as a buffer sodium racemic lactate 15 in insufficient quantity to prevent substantially lowering of the pH of said composition and consequent breaking of said emulsion.

2. A composition as described in claim 1, wherein 20 in the fatty ingredient is at least one constituent of lanolin.

3. A plastic embalming composition especially

adapted for hardening tissues from the outside of the body and of sufficiently solid consistency to adhere to the surface thereof, comprising an emulsion of formaldehyde in glycol stearate and oxycholesterin and including a buffer agent capable of preventing a substantial drop in pH of said composition and consequent breaking of said emulsion. 5

4. A composition as defined in claim 3, wherein the buffer is of the type of sodium racemic lactate, 10 sodium tartrate, and sodium citrate.

5. An embalming composition especially adapted for hardening tissues from the outside of the body and of sufficiently solid consistency to adhere to the surface thereof, comprising an emulsion of 15 formaldehyde in a fatty substance containing at least one constituent of lanolin, and including a buffer agent capable of preventing a substantial drop in pH of said composition and consequent 20 breaking of said emulsion.

HILTON IRA JONES.
